FIG. 1

FIG. 2

FIG. 3

FIG. 1 is a top plan view of a cover for gear shift mounting, embodying my new design.

FIG. 2 is a side elevational view of the same.

FIG. 3 is an end elevational view of the same.

The side of the device not shown, is the same as that shown in FIG. 2, and the end of the device not shown, is the same as that shown in FIG. 3.

The gear shift lever, shown fragmentarily in broken lines in FIGS. 2 and 3, is included for illustrative purposes only.

What I claim is:

The ornamental design for a cover for gear shift mounting, as shown and described.
